UNITED STATES PATENT OFFICE.

EDWARD SEAVER, OF NEEDHAM, AND FRANK A. MAZZUR, OF WABAN, MASSACHUSETTS; MATTIE P. MAZZUR, ADMINISTRATRIX OF SAID FRANK A. MAZZUR, DECEASED; ASSIGNEES TO PEABODY ENGINEERING CORPORATION, OF NEW YORK, N. Y., A CORPORATION OF NEW YORK.

COMBINATION OIL AND GAS BURNER.

Application filed February 6, 1925. Serial No. 7,371.

Our invention relates to a combination oil and gas burner whereby either gaseous or liquid combustibles may be efficiently burned without overheating of the parts and has 5 for its object to provide a device which will permit the change from one fuel to another in a minimum of time, as well as the use of both gaseous and liquid combustibles simultaneously during the period of change. 10 A further object is to provide a means of supplying a cooling medium to the heated parts through the gas chamber while burning oil and through the air register while burning gaseous fuel to prevent over-heating 15 and distortion of parts.

The foregoing and other features of our invention will now be described in connection with the accompanying drawing, forming part of this specification, in which we 20 have represented our device in its preferred form, after which we shall point out more particularly in the claims those features which we believe to be new and of our joint invention.

25 Figure 1 is a sectional view of our device illustrated within a standard air register supported in the wall of a furnace.

Figure 2 is a view of the diffuser end of 30 our device looking from the right, it being uniform throughout only half of it is shown.

In the carrying out of our invention we 35 employ a standard mechanical atomizer 1 with gun 2 and tip 3. Surrounding the gun 2 we provide a cylindrical gas chamber 4 comprising an inner and outer cylinder joined together at one end and held apart at the other end by the lantern ring spacer 5 and tip 11. The outer cylinder is supported 40 in the wall 6 of the air register 7 provided with the usual shutters 8 to regulate the air for combustion, peep hole 9, all of which is common to air registers used for the purpose. On the furnace end of the inner cylinder of the gas chamber 4 is the diffuser 10.

45 This diffuser is a device which acts as a partial shield to the oil spray, so that the air for combustion will not strike the spray with full force. Some air at this point is required, but it is necessary to supply it in a 50 small quantity and with a gentle velocity. As shown, the diffuser is formed with a series of openings, as usual, through which openings gas discharged from the gas cham-

ber passes into the oil spray and then into the combustion chamber. A tip or plug 11 55 is provided with a threaded portion 12 adapted to screw on the end of the inner cylinder, and a tapered portion 13 adapted to make tight contact with the outer cylinder of the gas chamber 4. A plurality of 60 pipes 14 are adapted to screw into holes 15 in the plug 11 and extend radially therefrom, conforming approximately to the conical shape of the diffusers in common use. These pipes are closed at their outer ends 65 but are provided with outlet holes 16 on the side of the pipes next the diffuser 10. The diffuser is conical in shape and resembles in form the diffusers in common use with the exception that it has two rings 17 and 18 70 formed integral therewith, said rings being provided with holes 20 through which the pipes 14 extend thereby holding the diffuser 10 to the plug or tip 11. The diffuser is provided with the openings 34 alternating with 75 the ribs 35, which in combination serve to diffuse the air and admit it in proper amount to the oil burner. A certain number of the openings 34, preferably every other one, as indicated in Figure 2, are provided with 80 extensions 36 toward the axis of the oil burner and the gas pipes 14 are so arranged as to discharge gas through the extended openings 36 and corresponding openings 34. 85 With this simple assembly the conical diffuser plate 10 is joined to the plug 11 by means of the pipes 14 thereby forming a diffuser which is connected to the gas chamber 4 and provided with outlet for gas 90 through the holes 16. It practically presents a hollow diffuser which may be used as a gas burner.

Near the closed end of the gas chamber 4 away from the furnace, we provide a plurality of holes or openings 30 which communicate to the inside of a fitting 31 surrounding the gas chamber 4. This fitting is provided with a plug 32 which may be removed when gas is not used to provide means for delivering air to the diffuser and 100 a threaded portion 33 for attaching a flexible gas hose or other pipe to any gas supply.

It will be apparent from the foregoing description that when the gas supply is shut off, the plug 32 can be removed connecting the gas chamber 4 with the air 105

surrounding the furnace and that this cold air will be delivered to the diffuser which will be sufficient to prevent excessive temperatures and thereby prevent distortion of 5 the parts.

It will also be apparent that when it is desirable to change from a gas burner to an oil burner that both gas and liquid combustibles may be burned during a period of 10 change, the mechanical atomizer will in that event deliver a spray inside the combustion chamber, that air for proper and efficient combustion will be delivered through the air register, and that gas will be delivered 15 into said spray through the diffuser.

We wish it distinctly understood that our combination gas and oil burner herein described and illustrated is in the form in which we desire to construct it and that 20 changes or variations may be made as may be convenient or desirable without departing from the salient features of our invention and we therefore intend the following 25 claims to cover such modifications as naturally fall within the lines of invention.

We claim:—

1. Fuel burning apparatus for furnaces comprising a liquid fuel atomizer, a diffuser surrounding said atomizer and having openings 30 therein, a chamber supported in proximity to said diffuser and having outlets in the wall thereof adapted to discharge a gaseous fuel through the openings in the diffuser, and a connection to said chamber 35 for supplying a gaseous fuel thereto.

2. Fuel burning apparatus for furnaces comprising a liquid fuel atomizer, a diffuser surrounding said atomizer and having openings 40 therein, a chamber supported in proximity to said diffuser and having outlets in the wall thereof adapted to discharge a gaseous fuel through the openings in the diffuser, a connection to said chamber for supplying a gaseous fuel thereto, and means

for admitting air to said chamber when the 45 gas supply is cut off.

3. Fuel burning apparatus for furnaces comprising a liquid fuel atomizer, a gas chamber surrounding the atomizer supply pipe, said chamber having outlets in the 50 wall thereof for the gas, and a diffuser supported on the furnace side of the gas chamber and in close proximity thereto, said diffuser having openings therein through which the gas is adapted to pass. 55

4. Fuel burning apparatus for furnaces comprising a liquid fuel atomizer, a gas chamber surrounding the atomizer supply pipe and having extensions therefrom with outlets for the gas, and a diffuser on the 60 furnace side of said extensions and in close proximity thereto, said diffuser having openings therein for the passage of the gas discharged from said extensions.

5. Fuel burning apparatus for furnaces 65 comprising a liquid fuel atomizer, a gas chamber surrounding the atomizer supply pipe, tubular extensions connected to said chamber, said extensions having gas discharge outlets, and a diffuser supported on 70 the furnace side of said extensions and having openings therein for the passage of gas discharged through the outlets in the said extensions.

6. Fuel burning apparatus for furnaces 75 comprising a liquid fuel atomizer, a gas chamber surrounding the atomizer supply pipe and having extensions therefrom surrounding the atomizer and having discharge outlets for the gas, and a conical shaped 80 diffuser having openings therein and supported upon said gas chamber on the furnace side of said extensions.

In testimony whereof we affix our signatures.

EDWARD SEAVER.
